CHARLES H. BAILEY, OF WHEELING, WEST VIRGINIA, ASSIGNOR TO JACOB HINKELMAN,
JAMES M. FEASER, AND DENNIS C. FAHEY, ALL OF WHEELING, WEST VIRGINIA.

CLOTHES-LINE REEL.

No. 892,349.

Specification of Letters Patent.

Patented June 30, 1908.

Application filed February 13, 1908. Serial No. 415,716.

To all whom it may concern:

Be it known that I, CHARLES H. BAILEY, a citizen of the United States of America, residing at Wheeling, in the county of Ohio 5 and State of West Virginia, have invented new and useful Improvements in Clothes-Line Reels, of which the following is a specification.

This invention relates to clothes line reels, 10 and one of the principal objects of the same is to provide a clothes line reel of simple construction and made of wire of the required gage which will be provided with means whereby both ends of the clothes line will be 15 held or gripped to prevent the line from unwinding.

Another object is to provide a clothes line reel, the body portion of which is to be made of nickel-plated or galvanized wire of the required gage, said reel being provided with a central shaft to which a handle is pivoted, 20 said shaft having a centrally disposed bend therein to engage a knot on the clothes line and to thus hold the one end of the clothes 25 line while it is being reeled up, a similar bend being formed in the body of the reel to engage the outer end of the clothes line or to engage the clothes line at any point to prevent unwinding.

These and other objects may be attained 30 by means of the construction illustrated in the accompanying drawing, in which:—

Figure 1 is a plan view of a clothes line reel made in accordance with my invention. 35 Fig. 2 is a similar view showing a clothes line mounted upon the reel and having its outer end connected to the reel so that it will not unwind.

Referring to the drawing for a more specific description of my invention, the numeral 1 designates the body of the reel, 40 which is formed of wire of the required gage, said wire being either nickel-plated or galvanized. The reel body comprises the 45 guard members 2, the cross bars 3 upon which the line is wound and the central portion 4 which is contracted or bent slightly inward. The terminal ends of the body portion of the reel are formed into loops or

bearings 5 which are brought together in alignment, and the handle 6 is provided with a wire pintle 7 which extends through the handle and through the bearings 5, said pintle being upheaded at both ends and provided with a suitable washer 8, one at each end. 50 The handle 6 is permitted to turn upon the pintle 7, and the pintle 7 is permitted to turn within the bearing 5. A central shaft 9 is mounted in bearings 10, said bearings being formed in the frame of the reel by one coil or 55 bend in each side thereof, said shaft 9 being headed up, as at 11, and provided with a washer 12 at one side of the reel frame, while the opposite end of the shaft 9 extends through a handle 13 and is headed up, as at 60 14, against a washer 15 outside the handle. The shaft 9 is permitted to turn in the bearings 10, and the handle 13 is permitted to turn upon the shaft 9 when in use.

A substantially V-shaped bend 16 is 65 formed centrally in the shaft 9, the purpose of which is to clamp the inner end of the rope before said rope is wound upon the reel. A knot may be formed in the rope and placed in the notch 17 to hold the inner end of the 70 rope firmly in place. A similar bend 18 is formed immediately under the handle 6 to hold the outer end of the rope after it has been reeled, as shown in Fig. 2.

The operation of my invention may be 75 briefly described as follows: One end of the rope is secured in the notch 17 in the shaft 9, and by grasping the handle 13 in the left hand the reel is rotated by means of the handle 16 grasped in the right hand. After 80 the rope 19 has been wound upon the reel the terminal end 20 is secured in the notch 21, as shown in Fig. 2 of the drawing.

From the foregoing it will be obvious that 85 a reel made in accordance with my invention 90 is of simple construction, may be produced at low cost, is strong, durable and efficient for its purpose and will operate quickly to reel up a clothes line.

Having thus described the invention, what 95 is claimed as new, is:—

A clothes line reel comprising a body portion formed of wire, the terminal ends of

which form bearings for the pintle of a handle, a bend or notch in the body portion of the reel to hold the terminal end of the clothes line, bearings formed on the frame 5 centrally thereof, a shaft mounted to turn in said bearings, said shaft having a bend or notch therein to hold the inner end of the clothes line, and a wooden handle mounted to

turn upon the outer end of said shaft, substantially as described.

In testimony whereof I affix my signature in presence of two witnesses.

CHARLES H. BAILEY.
